CLAIM

The ornamental design for a combination dry bag, lift bag, and dive marker flag, as shown and described.

DESCRIPTION

FIG. 1 is a perspective view of a combination dry bag, lift bag, and dive marker flag showing my new design;

FIG. 2 is a front elevational view thereof;

FIG. 3 is a rear elevational view thereof;

FIG. 4 is a right edge view thereof;

FIG. 5 is a left edge view thereof;

FIG. 6 is a top plan view thereof; and,

FIG. 7 is a bottom plan view thereof.

The opposed triangular designs shown in FIGS. 1, 2 and 3 are lined for the color red.
